(57) **CLAIM**

The ornamental design for a footrest, as shown and described.

DESCRIPTION

FIG. 1 is a perspective view of a footrest showing my new design;

FIG. 2 is a front view thereof, a rear view being a mirror image of the front view;

FIG. 3 is a left side view thereof, a right side view being a mirror image of the left side view; and,

FIG. 4 is a top view thereof.

The broken lines shown in the drawings depict portions of the footrest that form no part of the claimed design.
